PHONOGRAPHIC TIME ANNOUNCER

Dean A. Herman, Fort Sill, Okla.

Application March 31, 1938, Serial No. 199,293

10 Claims. (Cl. 179—6)

(Granted under the act of March 3, 1883, as amended April 30, 1928; 370 O. G. 757)

This invention described herein may be manufactured and used by or for the Government for governmental purposes, without the payment to me of any royalty thereon.

5 This invention relates to time announcers; more particularly it is directed to a device of this character for use in telephone exchanges for supplying subscribers with the time of day.

One of the objects of the invention is to provide 10 a phonographic time announcer to supply continuous single-voiced time announcements which will simulate closely those given by the present day manual telephone announcer, thus eliminating the expense, fatigue and delay of operators in 15 large telephone exchanges in giving out the correct time.

Another object of the invention is to provide 20 a time service for telephone systems which will function to convey the correct time automatically, correctly, instantly and at any moment to give the correct time without having to depend upon human voice other than that provided on a record to convey the service to the subscriber.

This invention may obviously also be utilized 25 in the dissemination of other information such as weather and newspaper reports. Briefly stated, this invention consists generally in a phonographic record (disk) inscribed with sentences telling the various times of day, preferably one 30 for each minute during the twelve hours, which constitute the ordinary period in which the hour hand of a timepiece makes a complete revolution; a phonographic reproducer transmitter adapted to travel across said record, a telephone 35 transmitter connected to said phonographic reproducer transmitter; suitable propelling means for causing said phonographic reproducer transmitter to move across the record for reproducing said time announcements; a timepiece in connection with said propelling means; means including 40 a friction device for returning the reproducer transmitter to its initial starting position after completion of its travel across the record, and friction compensating means for assisting the 45 timepiece in operating the apparatus by creating a clockwise torque on the minute hand of the timepiece.

With the above and other objects and advantages in view, the invention consists of certain 50 features of construction and operation of parts which will hereinafter appear, and in which—

Fig. 1 is a top plan view of an electric phonograph embodying the invention;

Fig. 2 is a cross-sectional view taken on the line 55 2—2 of Fig. 1;

Fig. 3 is a side elevation of the invention applied to an electric phonograph;

Fig. 4 is a fragmentary perspective view thereof, and

Fig. 5 is a cross-sectional view taken on the line 5—5 of Fig. 4.

In the illustrated embodiment characterizing the invention 1 indicates a casing of a conventional electric phonograph in which a mechanism (not shown) is provided for revolving a turntable 2 having a record 3 mounted thereon. The turntable 2 is adapted to be rotated in the direction as indicated by the arrow, thereby rotating the record in the same direction.

The record 3 is adapted to be provided with 15 720 concentric grooves representing each minute during the twelve hours, which constitute the ordinary period in which the hour hand of a timepiece makes a complete revolution. For purposes of clearness the record 3 is illustrated as only 20 having a certain number of concentric grooves 4. In groove *a* of the grooves 4 is recorded the words twelve o'clock; in groove *b* the words twelve-one; in groove *c* twelve-two, etc., until in groove *y* the words eleven-fifty-eight, and in groove *z* the words eleven-fifty-nine. The record 3 is also provided with connecting grooves *a'*, *b'*, *c'*, etc. to *z'*, and with a starting and spiral groove 5 and 6 respectively. The grooves *a* to *z* connect the concentric grooves *a* to *z* to each 30 other and the groove 5 connects with the groove *a* and extends closely adjacent to the outer periphery of the record. The spiral groove 6 is provided at the center of the record and connects with the last groove *z* from which it continues spirally around an inclined raised portion 7 formed at the center of the record for causing a phonographic reproducer transmitter 8 to be raised from the record after having reproduced the time announcements in the grooves *a* to *z* 40 over a twelve hour period.

The apparatus used in causing the phonographic reproducer transmitter 8 to travel across the record for reproducing the time intervals recorded in the concentric grooves 4 and to return it to its initial starting position, together with the friction compensating means for assisting the timepiece in operating the apparatus, is mounted on a suitable framework 9 composed of a bottom plate 10 which is mounted on the upper surface of the phonograph casing 1 beneath the turntable 2, and extends from adjacent one side of the turntable 2 across to one side of the casing 1 where it is suitably bent to form a seat or sup- 50 55

port 11 for a timepiece 12, containing an hour-hand 13 and a minute-hand 14.

The framework 9 is provided with end bearing plates 15 and 16 and with an intermediate bearing plate 17 which provide a bearing support for the apparatus above the record 3. The end plate 15 and the intermediate plate 17 extend up from the bottom plate 10, adjacent opposite sides of the turntable 2 and record 3, where they are joined together by a propelling shaft 18 and a pivot rod 19. The shaft 18 is adapted to propel the reproducer transmitter 8 across the record and is provided with a threaded portion 20 containing square screw threads 21 which terminate at one end in an inclined portion 22 adjacent to the inner side of the intermediate plate 17. On the shaft 18 is an extension 23 which is connected at one end to the inclined portion 22 and passes through the intermediate plate 17 from which it extends across to the end plate 16. This propelling shaft 18 is adapted to be rotated by the minute hand 14 of the timepiece and could be connected directly to the minute hand, but in order to make the device more efficient, a pinion 24 is mounted on the shaft 18 adjacent to the inner side of the end plate 16 to increase the rotation of the propelling shaft and allow more thread per inch on the shaft. The pinion 24 of the propelling shaft 18 meshes with a gear 25 mounted on an extension shaft 26, which extends through the end plate 16 where it is connected to the minute-hand 14 of the timepiece 12. The inner end of the minute-hand extension shaft 26 is adapted to project into a horizontal bore 27 provided in the outer end of a short horizontal projecting portion 28 of a gear 29 having a horizontal projecting threaded portion 30 provided on its opposite side from the portion 28. The threaded portion 30 of the gear 29 is adapted to threadably engage the outer end of an internally threaded sleeve 31, the inner end of said sleeve being secured to the intermediate plate 17 by screws 32 or the like.

A drum 33 is mounted on the shaft 26 which is held in place thereon by a shoulder 34 formed on the shaft 26, at one side of the drum and by a saw-toothed wheel 35 which is mounted on the shaft 26 at the other side of the drum. The saw-teeth on the wheel 35 are adapted to be engaged by hook-like dog members 36, as illustrated in Fig. 4, which are pivotally connected to the outer face of a flange 37, on one end of the drum. A rope 38 is attached by one end to the drum 33 and is wound thereon in a clockwise direction from where it extends downwardly through an opening 39 formed in the bottom plate 10. The free end of the rope 38 is provided with a weight 40 whereby friction compensating means are provided for assisting the timepiece 12 in operating the apparatus by creating a clockwise torque on the minute-hand extension shaft 26, in a manner to be hereinafter described. The inner end of the drum 33 is connected at one end to a plurality of horizontal pins 41, the other or inner ends of the horizontal pins 41 being adapted to slide in horizontal bores 42 formed in the outer end of the projecting portion 28 of gear 29. The gear 29 is adapted to be rotated in a counter-clockwise direction by a pinion 43 which is smaller in diameter but larger in width than the gear 29. The pinion 43 is provided on the outer end of a return shaft 44 which is adapted to engage with a hook 45 provided on the rear edge of the intermediate plate 17 at a particular point in the operation of the apparatus, and the shaft 44 is

also provided with a threaded portion 46 which terminates in an enlarged inclined threaded end 47. This shaft 44 is provided for returning the reproducer transmitter 8 to its initial starting position and has a pinion 48 on its inner end which is adapted to mesh with a crown wheel or ring rack gear 49 mounted on the forward side of a wheel 50 having a felt or rubber tire 51 provided on its outer surface. The crown wheel or ring rack gear 49 and the wheel 50 containing the rubber tire 51 are partially inclosed within a housing 52 which is closed at its underneath forward side by a curved portion 79 whereby an opening is provided in the bottom of the housing through which the lower end of the wheel 50 and tire 51 are adapted to extend below the open bottom housing 52, whereby the rubber tire 51 may frictionally contact with the record 3 for rotating the wheel 50 and gear 49 to thus rotate the return shaft through the pinion 48.

In order to unbalance the return shaft 44 and its connecting mechanism, counterweights 53 and 54 are provided. The counterweight 53 is secured to the free end of an elongated body portion 55, which is pivotally connected at its rear end to the rod 19 and return shaft 44 closely adjacent to the inner side of the intermediate plate 17, while the counterweight 54 is mounted on the outer end of an elongated body portion 80 which is connected at its inner end to the housing 52 of the friction device indicated generally by A, which is in turn pivotally mounted on the pivot rod 19. The friction device A which includes the gear 49, wheel 50 and rubber or felt tire 51 is pivotally mounted on the housing 52 by the shaft 40 which is arranged at right angles to the return shaft 44. In order to facilitate adjustment of the bearing frame 9 swivel adjustment screws 56 may be provided, which contact with the upper surface of the casing 1 and with the side edge of the bearing plates 15 and 17.

The reproducer transmitter 8 comprises a casing 57 which is divided into two compartments 58 and 59 by a vertically extending member 60 containing an opening 61. The casing 57 is closed at one side by a diaphragm 62 which is connected with the needle 63 of the reproducer transmitter by a rod 64. Adjacent to the opposite side of the portion 60 of the reproducer transmitter from the diaphragm 62 is a diaphragm 65 which is connected to one side of a box of carbon granules 66 by a small centrally located pin 67, the other side of the box of carbon granules 66 being connected to the inner end of a pin 67'. The opposite sides of the box of carbon granules 66 are connected to line wires 69 and 70 which line wires 69 and 70 form a part of the circuit to which subscriber telephones are attached. An ordinary telephone receiver 71, as shown in Figs. 1, 3 and 4, is connected to the telephone line wires 69 and 70 and illustrates the use of the apparatus. In the use of the apparatus in connection with telephone exchanges of course this telephone circuit passes through the exchange or central station.

The reproducer transmitter 8 is pivotally mounted on the rod 19 at its lower end substantially at the middle portion of its pivoted connection with the guide rod 19 and is provided with horizontally extending arcuate shaped threaded grooves 72 and 73, formed on the front and rear of the reproducer transmitter on opposite sides of the pivoted connection of the reproducer transmitter with the guide rod 19. The threads 74 of the groove 72 are adapted

to engage the square screw threads 21 of the propelling shaft 18 in such a manner that the reproducer transmitter needle 63 is caused to engage in the first groove *a* of the record 3 when the hands 13 and 14 of the timepiece 12 are at twelve o'clock. The arcuate threaded groove 73 of the reproducer transmitter is formed slightly higher on the casing 57 than the arcuate groove 72 and the rear follower threads 75 thereof are adapted to engage the screw threads 76 of the threaded portion 46 on the return shaft 44 when the reproducer transmitter is to be returned to its initial starting position. The threads 76 of the return shaft 44 should slope in an opposite direction from the threads 21 of the drive shaft 18. On the upper end of the reproducer transmitter is a horizontally extending tube 77 containing a freely movable metal ball 78 which is adapted to unbalance the reproducer transmitter 8 either in a forward or rearward direction when the reproducer transmitter has reached its travel across the record and is to be returned to its initial starting position by the return shaft 44 and also after it has been returned to its starting position.

In the operation of the mechanism assuming that the hands 13 and 14 of the timepiece 12 are at twelve o'clock with the minute hand 14 moving to the right or in a clockwise direction, as indicated by the arrow in Figs. 2 and 4. This movement of the minute hand 14 rotates the extension shaft 26 and gear 25, which in turn rotates the pinion 24 in a counter-clockwise direction thereby rotating the propelling shaft 18 in the same direction.

The reproducer transmitter 8 having been placed to the right at its initial starting position with the metal ball 78 in the forward end of the tube 77, the front end of the reproducer transmitter is caused to move down the inclined portion 22 of the propelling shaft 18 by means of the arcuate groove 72, whereby the reproducer transmitter needle 63 engages in the deep starting groove 5 which guides the needle to the first groove *a* of the concentric grooves 4, provided on the record 3. The needle 63 by traversing the concentric groove *a* will thereby actuate the diaphragms 62 and 65 of the reproducer transmitter for varying the resistance of the box of carbon granules 66, thereby causing the reproducer transmitter to announce over the telephone line wires 69 and 70 to the subscriber the words twelve o'clock. The needle 63 having traversed the groove *a* the reproducer transmitter will then be moved horizontally toward the center of the record by the thread 74 of the threaded groove 72 of the reproducer transmitter engaging the square threads 21 of the propelling or drive shaft 18, exactly the distance between grooves *a* and *b* when the minute hand 14 of the timepiece has moved forward one minute at twelve-one, the needle 63 being guided to groove *b* by the connecting groove *b'*. The needle 63 will then continue to move around the groove *b* until the minute hand of the timepiece moves to two minutes after twelve o'clock, thus causing the reproducer transmitter to announce the word twelve-two over the telephone line wires 69 and 70, at which time the needle 63 will move to groove *c* by its connecting groove *c'*, etc. This movement to each of the concentric grooves *a* to *z* is assisted by the rotation of the drive shaft 18 which produces friction that tends to raise the forward end of the reproducer transmitter and hence its needle 63

so that the needle may be caught by the connecting grooves *a'* to *z'*. When the hands 13 and 14 of the timepiece 12 have reached the time of eleven-fifty-nine, or one minute of twelve, the needle 63 will be in the last groove *z* of the record 3. As the minute-hand 14 of the timepiece turns to twelve o'clock the last thread of the threaded groove 72 of the reproducer transmitter is thrown clear of the last thread 20' of the propelling or drive shaft 18. This lurch 10 of the reproducer transmitter carries the needle 63 to the beginning of the spiral groove 6 which continues to carry the needle toward the center and raises it up the inclined portion 7 of the record. The pitch of the screwthreads 21 of the propelling or drive shaft 18 and the speed of this shaft 18 are such that the speed of the reproducer transmitter and needle across the record are properly timed with relation to the grooved record 3.

Obviously in the operation of the system it is necessary to return the reproducer transmitter to its starting position after being extended over a twelve hour period. The return mechanism is such that the reproducer transmitter is returned to its starting position in a fraction of a minute and consequently there is no interference with the time keeping by such action.

In the operation of the return mechanism, the return movement of the reproducer transmitter is begun when the needle 63 nears the top of the inclined portion 7 of the record 3. This upward movement of the needle 63 raises the forward end of the reproducer transmitter and causes the tube 77 to be in an inclined or slanting position from the horizontal which causes the freely movable metal ball 78 to roll through the tube to the rear which unbalances the reproducer transmitter and moves it about its pivoted connection with the guide rod 19 in a rearward direction, whereby the rear follower threads 75 of the arcuate groove 73 at the rear of the reproducer transmitter are caused to threadably engage the screw threads 76 of the return shaft 44. The weight of the ball 78 also begins to unbalance the return mechanism including the friction device A, thereby lowering the ring rack gear 49 and the wheel 50 downwardly until the felt or rubber tire 51 on the wheel 50 frictionally contacts with the rotating record 3. As the tire 51 comes into contact with the upper surface of the record 3, the wheel 50 and gear 49 are rotated in the opposite direction from the record or in a counter-clockwise direction, which in turn rotates the pinion 48 in mesh with the gear 49 in a clockwise direction and hence the return shaft 44 in the same direction, whereby the reproducer transmitter is screwed to the right on the return shaft 44 to the inclined threaded portion 47 thereof which is enlarged in diameter so that as the reproducer transmitter 8 reaches its starting position the threads provided on the enlarged portion 47 raise the rear of the reproducer transmitter upwardly until the rear of the tube 77 is higher than its front end, thus causing the ball 78 to roll forward overbalancing the reproducer transmitter in a forward direction to its starting position.

After this return movement of the reproducer transmitter which takes place in a fraction of a minute, the needle 63 of the reproducer transmitter 8 is again caused to slide down the enlarged inclined portion 22 of the propelling shaft 18 from where it is again guided to the first groove *a* by the starting groove 5. As the reproducer

transmitter topples forward the return mechanism is overbalanced forward on the rod 19 by the counterweights 53 and 54, thereby raising the housing 52 from the record and the friction device A. When the wheel 50 of the friction device A clears the record 3 this overbalancing movement is stopped by the return shaft 44 engaging the hook 45 provided on the rear edge of the intermediate bearing plate 17. At twelve o'clock 10 when the return mechanism is unbalanced on the guide rod 19 for the return of the reproducer transmitter to its initial starting position by the return shaft 44, the pinion 43 on the outer end of the shaft 44 is also moved downwardly with 15 the return shaft and meshes with the gear 29 thereby causing the gear 29 to rotate in a counter-clockwise direction. This counter-clockwise rotation of the gear 29 causes the drum 33 also to be rotated in a counter-clockwise direction 20 through the pins 41, thus disengaging the dog members 36 on the drum from the saw-teeth of the wheel 35 of the minute-hand extension shaft 26 and causes the rope 38 to be wound up on the drum, thus pulling the weight 40 upwardly. As 25 the weight 40 moves upwardly, the gear 29 being rotated in a counter-clockwise direction by the pinion 43 is caused to be screwed to the right, due to the pitch of the threads provided on the threaded portion 30 of the gear 29 and of the 30 threads in the casing 31. At the moment that the weight 40 is moved completely up the gear 29 is moved far enough to the right to disconnect from the pinion 43. At this instant the dog members 36 then reengage the saw-toothed wheel 35, 35 whereby the weight 40 pulling down on the rope 38 causes the drum to rotate in a forward or clockwise direction, thus introducing a clockwise torque on the minute-hand extension 26 which is exactly equal to the friction set up in the extension shaft 26 and the propelling shaft 18.

Alternate methods of combining a phonograph reproducer and telephone transmitter into a single unit may be provided such as omitting the diaphragms entirely from the reproducer transmitter and fastening the needle arm of the reproducer transmitter to the carbon-electrode of the transmitter so that the vibrations of the needle are transmitted metallically to change the pressure on the carbon granules of the transmitter or with the additional connection of a stabilizing diaphragm of thin metal to soften or cushion the vibrations of the needle arm. Also use may be made of a simplified type of phonographic time announcer consisting merely of the phonograph with turntable, the pivot or guide shaft set in a frame with a record on each concentric groove of which is recorded a short weather forecast or other announcement. In this case the reproducer transmitter is merely placed by hand 45 so that it will continually announce any information that is desired. The circuit to the mechanism which revolves the turntable can easily be closed automatically as an incoming call is connected in and disconnected automatically when the calling circuit is broken. In this way undue wear on the record and other mechanism will be prevented.

It will thus be seen that there is provided a 70 highly new and useful form of phonographic time announcer which is well adapted for all the purposes intended. Even though there has been described and claimed certain features of construction and operation of parts, it is nevertheless to be understood that various changes may be made

therein without departing from the spirit or scope of the invention.

Having described my invention, what I claim as new and wish to secure by Letters Patent is:

1. In a phonograph announcer having a record thereon; a reproducer transmitter including a needle guided to move on the record; driving means to feed the reproducer transmitter toward the center of the record; lifting means on the central portion of the record to raise the needle and reproducer transmitter; and means including a friction device adapted to be driven by the record for returning the reproducer transmitter to its starting position, after the reproducer transmitter is raised.

2. In a phonograph announcer having a record thereon; a reproducer transmitter including a needle guided to move on the record; driving means to feed the reproducer transmitter toward the center of the record; lifting means on the central portion of the record to raise the needle and reproducer transmitter; means including a friction device adapted to be driven by the record for returning the reproducer transmitter to its starting position, and a friction compensating device connected to be operated by the driving means and a portion of the means for returning the reproducer transmitter to its starting position, whereby the driving means is assisted in feeding the reproducer transmitter toward the center of the record.

3. In a phonograph announcer having a movable grooved record; a reproducer transmitter including a needle guided to move on the record; clockwork driving means to feed the reproducer transmitter toward the center of the record; lifting means on the central portion of the record to raise the needle and reproducer transmitter; a screw threaded return shaft above the record, a friction device connected with said return shaft and adapted to be driven by the record for driving said return shaft; and means on the reproducer transmitter to engage the screw threads on said shaft after the reproducer transmitter is raised, whereby the reproducer transmitter is returned to its starting position on the record.

4. In a phonograph announcer having a disk record; a reproducer transmitter including a needle guided to move on the record; clockwork driving means including a screw threaded propeller shaft above the record to feed the reproducer transmitter to the center of the record; lifting means on the central portion of the record to raise the needle and reproducer transmitter; a screw-threaded return shaft above the record parallel with the propelling shaft and at the rear of the reproducer transmitter; a friction device connected with said return shaft and adapted to be driven by the record for driving said return shaft and means on the reproducer transmitter to engage the screw threads on said return shaft after the reproducer transmitter is returned to its starting position.

5. In a phonograph announcer having a disk record bearing a plurality of recorded time announcement grooves; a reproducer transmitter including a needle guided to move on the record; clockwork driving means including a screw-threaded propelling shaft above the record to feed the reproducer transmitter to the center of the record; a spirally grooved raised portion on the central portion of the record to raise the needle and reproducer transmitter; a friction device adapted to be driven by the record; a screw-threaded return shaft connected to be driven by
